UNITED STATES PATENT OFFICE

JOHN F. MAURER, JR., OF WOODCLIFF, NEW JERSEY

BOTTLE CRATE

Application filed March 14, 1928. Serial No. 261,540.

This invention relates to crates or boxes which are particularly designed for transporting milk bottles although not necessarily limited to such use, and the same is in 5 the nature of an improvement over my prior United States Letters Patent Nos. 1,635,133 and 1,328,748.

The invention primarily comprehends in a 10 crate which includes transverse and longitudinal brace rods, nonmetallic vertically arranged partition elements of a size and spaced in such a manner as to prevent contact of the bottles with each other and with the rods for the purpose of reducing chipping and 15 breakage of the bottles, as well as minimizing the noise incident to the transportation and delivery of the bottles.

As a further object, the invention comprehends improved partition elements of the 20 character described which serve as a means for supporting cracked ice around the upper portion of the bottles at and above the cream line, thus permitting the ice drippings to run down and cool the remainder of the bottles in which the milk is contained.

As a still further object, the invention contemplates partition elements which effect a sufficient frictional gripping of the bottles 30 to prevent displacement thereof when the crates are tilted or set on end.

The invention further embodies in a crate of the character set forth, a slatted bottom construction composed of transversely spaced slats spaced apart a distance slightly greater than the diameter of the bottle necks and spaced apart a distance slightly less than the diameter of the bottoms of the bottles, together with brace rods extending medially between the slats and below the upper surfaces thereof whereby the bottles when inverted will be supported by their neck ends resting upon said rods, so that the crates filled with the inverted bottles may be passed 40 through a suitable spray jet washing machine.

Another object of the invention is to provide the transversely spaced slats aforesaid with bevelled upper edges which function to cause the bottles to center within each of the 50 receiving compartments formed between the

longitudinal and transverse brace rods when the bottles are inserted into the latter in inverted positions.

Other objects of the invention reside in the comparative simplicity of construction 55 of the crate, the economy with which the same may be produced and the general efficiency derived therefrom.

With the above recited and other objects in view, reference is had to the following description and accompanying drawings, in which there is exhibited one example or embodiment of the invention, while the claims define the actual scope of the same.

In the drawings, Figure 1 is a top plan 65 view of a crate constructed in accordance with the invention.

Figure 2 is a longitudinal sectional view therethrough taken approximately on the line 2-2 of Figure 1, illustrating the bottles 70 in place and the manner in which the cracked ice is supported by the partition members.

Figure 3 is a transversely fragmentary sectional view taken approximately on the line 3-3 of Figure 1 and illustrating the bottles 75 in their inverted position.

Referring to the drawings by characters of reference, the crate includes side and end walls 10-10 and 11-11 and transversely spaced side and intermediate longitudinally 80 extending slats 12-12 and 13-13. The side slats 12 have inwardly beveled or inclined upper surfaces 14 while the intermediate slats 13 have oppositely beveled or chamfered upper corners 15, the purpose of which will 85 be hereafter set forth. The crate is further divided with longitudinal upper and lower brace rods 16 and 17 and transverse upper and lower brace rods 18 and 19 which are suitably attached to the end and side walls 90 10 and 11 respectively. The lower longitudinal brace rods 17 are disposed in a plane below the upper surfaces of the bottom slats 13 and 14, and in addition to serving as brace rods are adapted to support the necks N of 95 the bottles B when the same are inverted in the crate. To permit the necks to extend below the upper surfaces of the bottom slats, the said bottom slats are spaced apart a distance slightly greater than the diameter of 100

the bottle necks, whereas the spacing of said slats is slightly less than the diameter of the bottoms of the bottles in order that the bottles will be supported when in an upright position upon the upper surfaces of the slats and above and out of contact with the lower longitudinal brace rods 17.

In order to provide means for partitioning the crate to separate the bottles from contact with each other and from contact with the brace rods 16, 18 and 19, vertically disposed longitudinally and transversely spaced nonmetallic partition elements are superimposed upon the intermediate bottom slats 13 and extend upwardly therefrom to a point approximately where the cream line L obtains. The partition elements 20 are preferably in the nature of wooden posts approximately square having chamfered or beveled corners 21 which are further intersected at the upper ends by beveled portions 22. In order to connect the partition elements or posts 20 within the intermediate slats 13 to prevent shifting of the elements or posts, dowels 23 extend partially into the bottom of the elements and partially into the slats. The transverse dimensions of the partition elements or posts 20 are such as to frictionally grip the bottles and maintain the same out of contact with each other and with the wires or rods 16, 18 and 19.

In use, when the filled bottles are arranged in the crate, as illustrated in Figure 2, it will be observed that the upper ends of the partition elements or posts 20 which substantially fill in the space between the bottles serve to support cracked ice I around the upper portion of the bottle which contains the cream and which incidentally is subject to souring action quicker than the milk contained therebelow. The drippings from the cracked ice I flowing over the remaining lower portions of the bottles is sufficient to maintain the milk cool and against souring action. The frictional engagement of the partitions with the bottles is sufficient to prevent their displacement when the crate is tilted or set on end, and it is obvious that due to the fact that the bottles are maintained in a position out of contact with the metal rods and are engaged only by non-metallic or wooden surfaces, chipping, breaking or rattling of the bottles in transit or in handling of the crates is prevented or minimized.

In view of the fact that it is the common practice to cleanse the bottles by inverting the same in the crate and passing the crate through a washing machine in which jets of cleansing solution are projected upwardly through the slatted bottom, the present crate is ideally adapted for this purpose, and it follows that when the bottles are inverted the necks N, which are of a diameter less than the spacing of the bottom slats, will fall in between and rest upon the lower longitudinal

rods 17. In this connection, the upper inclined surfaces 14 of the side slats 12 and the upper chamfered or beveled corners 15 of the intermediate slats serve to guide the necks into the proper position illustrated in Figure 3.

Having thus described my invention, I claim:

1. A milk bottle crate comprising a body open at its upper and lower sides, slats spaced across and within the lower side of said body for supporting the bottles in an upright position thereon, and members also extending across the lower side of said body and between the said slats, said members being disposed below the upper sides of said slats to support the bottles thereon when the latter are inverted.

2. A milk bottle crate including end and side walls, a bottom wall composed of transversely spaced slats spaced apart a distance slightly greater than the diameter of the bottle necks and spaced apart a distance slightly less than the diameter of the bottle bottoms, longitudinal and transverse brace rods carried by the side and end walls of the crate, certain of the longitudinal brace rods being disposed centrally between adjacent slats and in a plane below the upper surface of the slats whereby the bottoms of the bottles are supported above and out of contact with said brace rods and whereby the bottles when inverted will be supported from the said brace rods by their neck ends.

3. A milk bottle crate including end and side walls, a bottom wall composed of transversely spaced slats spaced apart a distance slightly greater than the diameter of the bottle necks and spaced apart a distance slightly less than the diameter of the bottle bottoms, longitudinal and transverse brace rods carried by the side and end walls of the crate, certain of the longitudinal brace rods being disposed centrally between adjacent slats and in a plane below the upper surface of the slats whereby the bottoms of the bottles are supported above and out of contact with said brace rods and whereby the bottles when inverted will be supported from the said brace rods by their neck ends, the said slats having chamfered or beveled upper surfaces for guiding the bottle necks when inverted between the slats to rest upon the longitudinal brace rods which are disposed between the slats.

4. A milk bottle crate comprising a body open at its upper and lower sides, slats spaced across and within the lower side of said body for supporting the bottles in an upright position thereon, and members also extending across the lower side of said body and between the said slats, said members being disposed below the upper sides of said slats to support the bottles thereon when the latter are inverted, the upper opposed edges of said

slats being chamfered or beveled to guide the bottles into positions of rest on said members when inverted.

- 5 A milk bottle crate comprising a body open at its upper and lower sides, slats spaced across and within the lower side of said body for supporting the bottles in an upright position thereon, means for dividing the interior of said body into a plurality of bottle receiving compartments above said slats, and members also extending across the lower side of said body and between the said slats, said members being disposed below the upper sides of said slats to support the bottles thereon
10 when the latter are inverted, the upper opposed edges of said slats being chamfered or beveled to guide the bottles into positions of rest on said members when inverted.
15

Signed at New York in the county of New York and State of New York this 12th day of March, A. D. 1928.
